UNITED STATES PATENT OFFICE.

HENRY MILLER, OF MILWAUKEE, WISCONSIN, ASSIGNOR TO A. O. SMITH CORPORATION, OF MILWAUKEE, WISCONSIN, A CORPORATION OF NEW YORK.

OFFSETTING-PRESS.

1,340,138.

Specification of Letters Patent. Patented May 11, 1920.

Application filed March 30, 1918. Serial No. 225,791.

To all whom it may concern:

Be it known that I, HENRY MILLER, a citizen of the United States, residing at the city of Milwaukee, county of Milwaukee, 5 and State of Wisconsin, have invented new and useful Improvements in Offsetting-Presses, of which the following is a specification.

My invention relates to improvements in 10 offsetting presses for sheet metal blanks.

One object of my invention is to provide means for exerting pressure against the edge margins of a sheet metal blank or set of blanks in such a manner as to distort the blank laterally between the planes of its flat or side surfaces, thereby converting a flat strip or sheet of metal having straight side margins into a strip or sheet having approximately the same thickness, but with 15 one side margin indented or pressed inwardly and the other side margin correspondingly bulged or pressed outwardly, without otherwise distorting the stock.

Another object of my invention is to provide improved means whereby a strip of 20 sheet metal of a certain gage, (i. e., thickness), may be clamped and subjected to edge pressure in such a manner as to produce a sheet or strip of different thickness or of 25 differing thicknesses in different portions thereof.

My invention is of peculiar value in the manufacture of sheet metal frame bars for 30 motor driven vehicles and other metallic frames in cases where the completed bars are curved at one end or at points intermediate of their ends, and also in cases where it is desirable to form a bar from sheet metal with one portion thin and wide, 35 and another portion relatively narrow and thick.

I not only provide means for producing a blank of the required size, thickness, and contour in a single operation performed 40 upon an originally rectangular strip or sheet of metal, but I also contemplate the provision of means whereby bending operations may be performed simultaneously upon a series of such strips by means of a, 45 single press so arranged that the blanks may be readily removed after a bending operation and another set of blanks inserted during the short interval that the pressing

head is retracted in a machine which is being continuously operated.

The offsetting press herein disclosed is 55 designed to effectuate the process of bending metal plates in the direction of their width, as claimed in application Serial #370,136, filed March 30, 1920, by R. Stanley Smith.

In the drawings:—

Figure 1 is a side elevation of a press embodying my invention.

Fig. 2 is a plan view of the same.

Fig. 3 is a fragmentary view of the stationary and movable members of a vertically acting drawing press embodying my invention, in modified form.

Fig. 4 is a fragmentary view of a further 70 modification.

Fig. 5 is a plan view, on a reduced scale, of a strip of sheet metal as it appears preparatory to the pressing operation.

Fig. 6 is a view of the same after it has 75 been subjected to an offsetting operation in my improved press.

Fig. 7 is a view of a blank formed from a strip of metal like that shown in Fig. 5, in which the press has been used to both 80 bend and thicken portions thereof.

Like parts are identified by the same reference characters throughout the several views.

In Figs. 1 and 2, a table 1 is supported 85 from a bed 2, and is provided in its upper surface with a table plate 3 adapted to receive the work, comprising a blank, or, if desired, a set of sheet metal blanks 4. The table is provided with an upwardly projecting shouldered portion 5 near its front end, against which a stationary matrix is seated. This matrix preferably comprises a separate or separable member interchangeable with other and similar matrices of differing thickness and contour, but it is not essential to my invention in its broader aspects whether the matrix be separable or integrally formed. The inner margin of the matrix constitutes a work shaping face 100 or die, and in the construction illustrated in Fig. 1, the matrix is of sufficient thickness to receive several sheet metal blanks 4, the latter being placed in a horizontal position upon the table plate 3 with their edges 105 substantially in abutting contact with the

more rearwardly projected portions of the die.

The contour of the die corresponds, of course, to the desired edge contour to be imparted to the blanks.

A movable die member 7 is actuated along the table plate 3 by means of a clamping head 8. This movable member has a working face which inversely conforms in contour to the contour of the working face of the matrix, and it is arranged to bear against the work in direct opposition to the matrix, and in the plane of the work. Where the matrix is interchangeable with others of the desired contour or thickness, the movable die members 7 will also be made removable from the head 8 and interchangeable with others corresponding, in each case, with the substituted matrix in thickness and also inversely as to contour.

In the construction shown in Fig. 1, the clamping head 8 is connected with a slide 10, which is loosely interlocked with the table 1. The head 8 has a shouldered portion 12, against which, the rear margin of the die member 7 is seated, whereby, when the clamping head is moved forwardly, the die member will be brought into pressure contact with the work.

The clamping head 8 is provided with a forwardly projecting work clamping portion 14, the under surface of which is preferably provided with a removable face or platen 15 adapted to bear upon the upper surface of a blank 4 supported by the table plate 3 between the die members, the die having substantially the same thickness as that of the blank, (or pile of blanks if more than one blank is to be shaped in a single operation). It is not essential, except for the purpose of interchangeability and replacement, whether the face plate 15 and shouldered portion 12 be separately formed or whether these parts be formed integral with the head 8 and with the die member 7.

The clamping head 8 may be actuated from any suitable source of power exerted obliquely to the upper surface of the table and in the direction of the matrix, or stationary die member 6. In the construction illustrated, the power is applied from a driving pulley or wheel 20 through shaft 21, pinion 22, gear wheel 23, shaft 24, pinion 25, gear wheel 26, shaft 27, eccentrics 28, carried by shaft 27, and connecting arms or rods 29, the latter being pivotally connected with the clamping head 8 by cross pins or bolts 30, whereby a slow but powerful reciprocating movement is transmitted to the head 8. The length of the stroke is sufficient to withdraw the clamping head from the work during the retractive stroke, the clamping head being then in the position indicated by dotted lines in Fig. 1. The blanks will therefore be uncovered and they

may then be removed and another set of blanks substituted preparatory to the next forward movement of the clamping head. The latter returns to the blank covering position before the movable die member 7 commences to exert effective pressure upon the blank or blanks.

Referring to Fig. 3, it will be observed that my invention is also applicable to an ordinary drawing press having a vertically reciprocating plunger. This may be accomplished by providing the bed 35 of such press with a work holder 36 having an upwardly extending oblique wing flange 37, the front or work receiving face 38 of which terminates at its lower margin in a shoulder 39 projecting at right angles thereto. In this construction, the stationary die member or matrix 41 is supported upon the shoulder 39 and against the inclined face 38. It has a contoured shoulder 40 to receive the lower edge or edges of the work and a thinner portion 41' extends upwardly along the inclined surface 38 and forms a bearing surface for the flat side of the blank corresponding with the bearing surface afforded by the table plate 3 in Fig. 1.

The plunger 42 in Fig. 3 is provided with a depending head 43 carried by a slide 44. The latter is adapted for horizontally yielding movement along the slide way provided on the plunger, such movement, however, being resisted by a compression spring 45, which normally pushes the slide against a stop 47. The head 43 is provided with an inclined face 48 which is parallel with the inclined face 38 of the matrix and work holding member, and the movable die or tool 49 is secured to this inclined face near its upper margin. This die member also has a contouring shoulder 50 and a work clamping portion 51, the latter corresponding functionally with the plate 15 in Fig. 1.

The arrangement is such that, when the plunger 42 is depressed, the work clamping portion 51 of the die will move into sliding contact with the blanks 4', and thereafter the die shoulder 50 will engage the upper margins of the blanks and force them downwardly in the direction of the matrix 41. During this shaping movement, slide 44 will be retracted from stop 47 against the tension of the spring or springs 45, thereby allowing the head 43 to continue the downward movement until the blanks have been forced to conform to the contours of the opposing shoulders on the die members.

When the plunger 42 is retracted, the blanks will, of course, be released. The shaped blanks may thereupon be removed and replaced by other blanks preparatory to the next downward movement of the plunger.

In Fig. 4, I have illustrated a form of construction in which a relatively fixed die

member 54 is provided with a vertical face 55, and a contouring face or shoulder at 56. The movable member 58 is in the form of a vertically moving plunger having a 5 contouring face at 59 and a work clamping face at 60. The plunger operates between the fixed die member 54 and an upwardly projecting arm 62 carried by the support or table 63, the latter having another arm 10 or shouldered projection 64, against which, the die member 54 bears. This construction may be employed for relatively thin or soft stock, and in cases where a thickening of the stock as shown in Fig. 7 is not desired. 15 It is, of course, possible to allow some yielding movement of the member 58 and also of its backing 62, but if yielding movements are desired, the forms of construction shown in Figs. 1, 2 and 3 will be found to be much 20 better adapted for this work.

My invention is peculiarly adapted for shaping elongated strips of sheet metal, such as are used in manufacturing side bars for automobile frames. Fig. 5 illustrates one 25 of these blanks as it appears preparatory to the contouring operation performed by my improved press. Fig. 6 shows the same blank after it has been subjected to the shaping or drawing operation.

30 In Fig. 7, it will be observed that the completed blank has been thickened at *a* and *b*. This is accomplished by so contouring the die members as to force a reduction in the width of the strip along the portions which 35 it is desired to thicken, whether the portion is offset or not. The pressure exerted upon a given area of the material by the movable die member is greater than that exerted upon an equal area by the clamping member 40 or platen, and the latter is adapted to yield resiliently under pressure developed by the thickening of the material.

While I prefer to apply the power along lines oblique to the die faces, as indicated 45 in Figs. 1, 2, and 3, in order that the resistance of the clamping platen may automatically increase in proportion to the offsetting pressure applied to the movable die, it will be understood from Fig. 4 that this 50 is not essential. It is also not essential that either die member should be formed as a separate or separable member from the shoulder or member against which it is placed, although I prefer to use separate 55 die members in order that they may be replaced or interchanged with other members of differing contour.

From the foregoing description, it will be 60 obvious that my invention may be utilized to thicken a blank without changing the contour of its edge margins by using dies having edge engaging surfaces which fit the margins of the blank throughout their length. In such cases, a rectangular blank 65 will remain rectangular and will be reduced

in width and increased in thickness. My invention also may be utilized to change the edge contour of a blank from that illustrated in Fig. 5 to that illustrated in Fig. 6 without materially altering the width or 70 thickness of the work, or if desired, variations in contour, thickness, and width may be made in a single operation.

My invention also provides means whereby the movable member may be made sufficiently thick and strong to withstand all strains to which it may be subjected during a shaping operation, for the reason that the pressure applying head is not limited in thickness to the thickness of the stock, but 75 includes also the thickness of the portion which laps upon the flat surface of the work and exerts a clamping pressure thereon. Even in the construction illustrated in Fig. 4, a clamping pressure is developed 80 as soon as the work starts to thicken or buckle under the pressure exerted by the shoulder 59. The movable member in this construction is not only reinforced by the table projection 62, but it is also made sufficiently thick and heavy to avoid any possible danger of breaking above the point where it enters the space between the projection 62 and the relatively fixed die member 54. 90

In the form of construction shown in Fig. 4, the movable head 58 is preferably recessed on its outer side, as indicated at 65, to reduce friction upon the projection 62.

While I have, for convenience in description, referred to the clamping head in Figs. 1, 2, and 3, as constituting a different element from that which is designated as the movable die member, it will be understood that, broadly speaking, the head is a part of 100 the die member, and these parts may, as above stated, be formed integrally. The same is true as to the fixed die member and the table or table plate 3.

It is possible to use the same press for 105 contouring blanks without materially thickening them, and for thickening them either throughout their length or in certain portions, and either in connection with contouring operations involving changes in marginal outline or otherwise, the results being dependent in part upon the form of the dies used and in part upon the length of the work shaping stroke, *i. e.*, the degree of movement of the movable die after the work 115 shaping operation commences.

Where any portion of the blank is being offset in such a manner as to change its marginal contour, there will be little, if any, tendency to thicken it until the shouldered 120 portions of the dies, which engage the edges of the blank, are in pressure contact, and with substantially equalized pressure, along the portion which is being offset for such 125 contouring operations. In such cases, there 130

will be some tendency for it to become thicker along the central portion of a margin which is bending concavely, and there will be some tendency for it to become thinner along a margin which is bending convexly, but this is true of all bending operations, and it is only where the pressure is continued after the stock has conformed to the contour of the die that a tendency will 10 develop for the stock to thicken throughout its width and develop pressure sufficient to cause the platen to yield.

In contouring flat plates, there is little tendency for the material to extend longitudinally at right angles to the direction in which the pressure is applied owing to the fact that not only the clamping pressure, but also the pressure developed along parallel lines throughout the entire length of the 20 blank, sets up counter pressures at all points, except at the extreme ends. Therefore if the pressure is continued after the edge engaging shoulders of the dies are not only in contact with the work throughout their 25 length, but in substantially equalized pressure contact, the blank will then become thickened throughout its length and width. But if in one portion of the blank, the edge pressure contact becomes equalized, while 30 in another portion offsetting movements are permitted, owing to the contour of the dies, then a continued movement of the movable die will offset where offsetting movements are permitted, and will thicken the work in 35 the area where no further offsetting can take place.

I claim:—

1. In an offsetting press for sheet metal blanks, the combination with a set of relatively fixed and movable clamping members 40 adapted to engage the side edges and flat surfaces of said blanks, and means for actuating one of said members against the edge of the blank and along one of its flat 45 surfaces, to offset the blank bodily.

2. In an offsetting press adapted for contouring sheet metal blanks, the combination of a work support provided with a contouring die face to receive one edge of the work, a movable member provided 50 with a correspondingly shaped contouring die face to bear upon the opposite edge of the work, and also having a portion which overlaps the work and is adapted to co-operate with the work support in resisting movement of the material of which the work is composed, in any other direction than that permitted by the contour of said die faces:

3. In an offsetting press, the combination 60 of two correspondingly contoured work shaping members, each adapted to bear upon work in a plurality of intersecting planes, and to exert pressure upon the work in opposition to the bearing surfaces of the 65 other member, means for actuating one of

said members to effect a relative approach of one of its bearing surfaces toward one of the bearing surfaces of the other member while maintaining the other bearing surface of the respective members in uniformly 70 spaced relation, whereby the work may be shaped by pressure developed by the approaching surfaces while the work is clamped between the other surfaces of said members.

75

4. In an offsetting press for sheet metal blanks, the combination of two blank shaping members having correspondingly contoured faces adapted to engage the side edges of the blank between them and also 80 having their faces adapted to engage the flat surfaces of the blank between them, and means for effecting a relative approach of the edge engaging faces while maintaining the other faces in substantially uniformly 85 spaced relation to each other.

5. In an offsetting press, the combination of two work shaping members having correspondingly contoured work shaping faces and also having opposing bearing faces in 90 planes substantially at right angles to the work shaping faces and spanning the space between the work shaping faces, and means for causing the work shaping faces to approach and recede while maintaining 95 the bearing faces in substantially uniformly spaced relation to each other.

6. In an offsetting press, the combination of a work support, relatively fixed and movable die members adapted to receive 100 one or more blanks between them upon the work support, a clamping member adapted to bear upon the work, and also adapted to engage and actuate the movable die member, and means for applying pressure to 105 the clamping member along an oblique line inclined to the support in the direction of the relatively fixed die member.

7. In an offsetting press adapted for contouring sheet metal blanks, the combination 110 of a work support, relatively fixed and movable die members adapted to receive the work between them upon said support, a clamping head adapted to bear upon the upper surface of the work, and also adapted 115 to actuate the movable die member, and means for applying pressure to the clamping head along an oblique line inclined to the support in the direction of the relatively fixed die member, whereby the work may 120 be clamped upon the support and subjected to pressure between the die members until the edges of the blanks, composing the work, are contoured to correspond with the contour of the die members.

125

8. In an offsetting press adapted for contouring sheet metal blanks, the combination of a work support, relatively fixed and movable die members adapted to receive the work between them upon said support, a 130

clamping head adapted to bear upon one flat surface of the work, and also adapted to actuate the movable die member, and means for applying pressure to the clamping head along an oblique line inclined to the support in the direction of the relatively fixed die member, whereby the work may be clamped upon the support and subjected to pressure between the die members until 5 the edge of the blanks, composing the work, are contoured to correspond with the contour of the die members, said clamping head being provided with a guide slidingly interlocked with the support, and 10 adapted to permit reciprocating movements 15 of said clamping head.

9. An offsetting press, including the combination of a work support adapted to receive the flat surface of a sheet metal blank, 20 a matrix having a contoured margin, means for holding the matrix with its contoured

margin in position to receive one side edge of the blank, a die member having a margin contoured as the counterpart of the matrix margin, and adapted to engage the 25 other side edge of the blank, a clamping head adapted to engage the die member and move it in the direction of the matrix, and means for applying pressure to the clamping head along an oblique line inclined to 30 the support in the direction of the matrix; said clamping head being formed to extend over the flat surface of the matrix in sliding contact therewith and clamping relation thereto. 35

In testimony whereof I affix my signature in the presence of two witnesses.

HENRY MILLER.
